UNITED STATES PATENT OFFICE.

LUIS ARNAVAT OLIVÉ, OF BARCELONA, SPAIN.

STOPPER FOR RENDERING BOTTLES NON-REFILLABLE.

1,291,093.

Specification of Letters Patent. Patented Jan. 14, 1919.

Application filed July 11, 1916. Serial No. 108,703.

To all whom it may concern:

Be it known that I, LUIS ARNAVAT OLIVÉ, a citizen of the United States of America, residing at 2 Obispo, Barcelona, in the Kingdom of Spain, have invented a certain new and useful Improved Stopper for Rendering Bottles Non-Refillable, of which the following is a specification.

The present invention relates to a stopper for rendering non-refillable, bottles to which it is fitted. The object of the invention is to provide a stopper of simple construction which is effective for its purpose.

The improved stopper will now be described with reference to the accompanying drawing, in which—

Figure 1 is an external elevation.

Fig. 2 is a longitudinal section of a stopper fitted to a bottle neck, inverted.

Fig. 3 is an analogous section but showing the bottle with its longitudinal axis horizontal.

Fig. 4 is a section on the line A—B of Fig. 2.

Figs. 5 and 6 represent details in plan.

The stopper consists of a hollow cylindrical casing 1 one end of which is provided with a valve supporting plate 2 forming a valve seat and fixed by means of a cement 21 applied beneath a flange 3 which serves by making a tight joint to prevent the adhesive material or cement from reaching the interior of the chamber in which the closing valve acts, as otherwise the regular operation of the valve would be impeded. The valve supporting plate 2 might also be connected with the receptacle 1 by means of a screw connection.

The obturating members are constituted by: the valve 4, the cylindrical float 5 and the pressure ball 6.

When the bottle 7 to which the stopper is fitted is upright, the valve 4 is applied to its seat on the plate 2, closing being then insured by the pressure of the ball 6 and of the float 5; when the bottle is inverted, the ball 6 rests upon its appropriate cup 8, so that, if the bottle should be immersed in a liquid, the float 5 will apply the valve 4 against its seat on the plate 2, thereby preventing the liquid from entering the bottle.

In the horizontal position (Fig. 3) the

ball 6 bears against a stop 9 provided with this object on the bottom of the casing 1, in such a manner that the ball 6, the float 5 and the valve 4 are firmly held between the said stop 9 and the plate 2, thus preventing communication between the bottle and the exterior, even if movement should be imparted to the bottle with the object of thereby causing a liquid to enter it.

An important feature of the improved stopper resides in the provision of a reduced length in the chamber of the casing 1, so that this chamber presents a shoulder 10 approximately corresponding with the middle part of the float 5; the object of this arrangement being that, when the bottle is inclined, the float may rock, thereby insuring its movement, any adherence between the chamber of the casing 1 and the float 5 being thus overcome. Such adherence would introduce a disturbing element into the functioning of the device.

On its inner face the plate 2 presents ribs 11, which are seen most clearly in Fig. 5, and which produce alternating restrictions of the inlet; this arrangement in conjunction with the orifices 12 intermediate of the ribs, serves the purpose that when the bottle 80 is inclined, for pouring out its liquid contents, the latter is split up into jets and the outer air is able to enter, so that the liquid issues uniformly and insures the functioning of the stoppering elements 4, 5 and 6 85 in such a manner that they do not impede the uniform flow of the liquid. With the same object, the non-return valve 4 comprises channels such as 15, or, instead of being provided on the valve, these channels 90 might be formed on the wall of the chamber of the receptacle 1 and produce the same effect; or they might be formed upon both parts.

When the bottle is intended to contain 95 oily or mucilaginous liquids, the seat member described is replaced by the seat member represented in Fig. 6 which in place of the outlets 12 presents a single, larger aperture 14 in the form of a star whose points act 100 in combination with the corresponding system of ribs 13, for the purpose already explained.

Discharge apertures 16 are arranged in

the bottom of the casing 1 in such a manner that their walls are very thin so that the edges will break readily if a wire should be introduced from the exterior with a view to 5 forcing the stoppering device so that the attempt is rendered obvious. The detail view Fig. 4 clearly shows the arrangement of the discharge orifices 16.

On the outer face of the portion 17 which 10 is of reduced diameter the receptacle 1 presents longitudinal channels to permit of permanently fixing to this portion a cylinder or lining 18 of cork or other appropriate material, intended to cause the stopper to fit 15 the bottle neck snugly.

The various parts of which the stopper that has been described is composed may be constructed of any suitable materials and they may be covered with a protecting coating 20 of varnish and, if thought desirable, a part (such for example as the outer thread 19) may be left unvarnished, so that it will be attacked if an acid should be used with the object of removing the stopper from the 25 bottle with fraudulent intent.

The improved stoppering device is applicable to all kinds of bottles, pots, jars and receptacles in general.

I claim:

30 1. A stopper for rendering bottles non-refillable, comprising a hollow cylindrical casing adapted to fit into the neck of the bottle and to contain the obturating means, viz: the valve, the float and the pressure ball 35 and having its upper end closed and provided with laterally disposed outlet holes inaccessible from the mouth of the neck, a valve supporting plate at the lower open end of the said hollow cylindrical casing, 40 said valve supporting plate having a number of holes therein, a continuous flat upper surface and an outwardly protruding flange secured to the lower end of the said casing, the said casing being provided near its 45 lower extremity with an inwardly protruding flange above the extreme edge of the casing making tight contact with the peripheral surface of the said valve supporting plate, a valve having flat top and bottom faces and 50 adapted to lie upon the flat upper surface of the said supporting plate, a float separate from the said valve and adapted to lie upon the valve, and a pressure ball adapted to lie upon the float, substantially as described.

55 2. A stopper for rendering bottles non-refillable, comprising a hollow cylindrical casing adapted to fit into the neck of the bottle and to contain the obturating means, 60 viz: the valve, the float and the pressure ball, and having its upper end closed and provided with laterally disposed outlet holes inaccessible from the mouth of the neck, the said casing being reduced to form an internal annular shoulder, a valve supporting

plate carried at the lower open end of the said casing, said valve supporting plate being provided with holes, a valve adapted to lie upon the said valve supporting plate and to close the said holes, a cylindrical 70 buoyant body mounted lengthwise in the hollow cylindrical casing and above the supporting plate in a position with the middle part of its length approximately corresponding to the internal annular shoulder formed 75 in the casing, and a pressure member adapted to lie upon the buoyant body, substantially as described.

3. A stopper for rendering bottles non-refillable, comprising a hollow cylindrical 80 casing adapted to fit into the neck of the bottle and to contain the obturating means, and having its upper end closed and provided with laterally disposed outlet holes 85 inaccessible from the mouth of the neck, the said casing being formed with thin frangible walls in a position immediately beneath the said laterally disposed outlet holes, a valve supporting plate at the lower end of the said hollow cylindrical casing and 90 secured thereto and having a flat upper surface, a valve adapted to lie upon the said valve supporting plate and to close the said plate, a buoyant body adapted to lie upon the said valve and a pressure member adapted 95 to lie upon the said buoyant body, substantially as described.

4. A stopper for rendering bottles non-refillable, comprising a hollow cylindrical 100 casing adapted to fit into the neck of the bottle and to contain the obturating means, and having its upper end closed and provided with laterally disposed outlet holes 105 inaccessible from the mouth of the neck, the said casing being formed of a reduced diameter at its lower end and forming an internal shoulder, longitudinal channels upon the exterior of the said reduced part of the casing, a fitting sleeve adapted to be applied upon the said reduced part of the 110 casing, a valve supporting plate carried at the lower open end of the said casing, the said valve supporting plate having a flat upper surface and being provided with holes, a valve adapted to lie upon the said 115 valve supporting plate and to close the said holes, a buoyant body mounted above the supporting plate in a position with its middle part corresponding to the internal shoulder formed in the casing and a pressure member 120 adapted to lie above the said buoyant body, substantially as described.

5. A stopper for rendering bottles non-refillable, comprising a hollow cylindrical 125 casing adapted to fit into the neck of the bottle and to contain the obturating means, and having its upper end closed and provided with laterally disposed outlet holes 130 inaccessible from the mouth of the neck, a valve supporting plate at the lower end of

the said hollow cylindrical casing and secured thereto, said plate having a flat upper surface, a valve adapted to lie upon the said valve supporting plate and to close the said 5 plate, a buoyant body mounted above the said valve and a pressure member adapted to lie upon the said buoyant body, the said elements being provided of a material at- tacked by an acid, a coating of a substance unattackable by such an acid applied upon all the said elements except at one part such as the reduced part of the casing upon which the fitting sleeve is applied, substantially as described.

LUIS ARNAVAT OLIVÉ.
